JOINT ARRANGEMENT

Louis I. Beckwith, Brookline, Mass.

Application December 2, 1937, Serial No. 177,733

2 Claims. (Cl. 211—135)

This invention relates to an improved joint construction for rack assemblies, and more particularly to the arrangement of a supporting bracket and of a cooperating shelf which is associated with the bracket.

The present invention is particularly suitable for employment in self-supporting, knock-down structures having separable joints, such as metal meat racks and other racks designed for heavy loads where rigidity and prevention of play between the parts are important requisites.

In accordance with this invention, an improved bracket is provided, which is adapted to be secured to an upright and which provides a vertical wall extending substantially tangentially to an opening through which the upright may be extend. The bracket also is provided with a second substantially vertical surface extending at right angles to the vertical wall, there being a horizontal web between the wall and surface. A boss or lug, which is preferably arcuate, extends upwardly from this web and has ends cooperating with the vertical surfaces in defining the walls of narrow slots for receiving the depending marginal flanges of the shelf. The shelf preferably may have a marginal frame formed by angle members, and its depending marginal flanges are preferably provided with protuberances in the form of indents which engage in the slots of the bracket with a wedge-like action. An arrangement of this character thus permits the firm interfitting engagement of the corners of the shelf with the bracket while affording a construction which is simple and relatively inexpensive to manufacture.

In the accompanying drawing:

Fig. 1 is a top plan view of a bracket constructed in accordance with this invention, the corner of the shelf which is supported by the bracket being indicated in dot and dash lines;

Fig. 2 is an elevational view of the bracket assembly shown in Fig. 1, a portion of the shelf being shown in section;

Fig. 3 is a perspective view of the corner portion of the shelf; and

Fig. 4 is a perspective view of the bracket.

The separable joint illustrated in the drawing is especially constructed for use in frames provided with vertical uprights and horizontal shelves supported between the uprights. The uprights preferably may be formed of round metal tubing, such an upright 1 being shown in Fig. 2.

In accordance with this invention, a bracket 4 may be provided with an opening 5 to receive the

upright, a clamp screw 6 being provided to clamp the bracket at the desired vertical position on the upright. The bracket 4 preferably is provided with a vertical wall 7 which is disposed substantially tangentially to the opening 5, and which is provided with a substantially vertical inner surface 8. In practice, the bracket 4 may be a casting and the wall 8 may have a slight downward and inward inclination. The bracket is also provided with a second substantially vertical surface 10. This surface may also have a slight inclination as shown. Between the surfaces 8 and 10 a horizontal web 15 is provided at the lower part of the bracket, and an integral boss or flange 19 extends upwardly from the web, the ends of this flange being arranged to cooperate with the surfaces 8 and 10 in defining narrow vertical slots. Preferably the ends of the flange 19 have a slight downward inclination, as shown in Figs. 1 and 4, and the flange may preferably have a curved outer surface and may be of arcuate form.

In accordance with this invention, a shelf is supported by a bracket 4 at each of its corners. The shelf may preferably be formed of metal and may have depending metal flanges to be received in the slots provided by each bracket 4. For example, as shown, the shelf 20 may have frame members in the form of metal angles 21, which are connected to each other by rivets 22 at the corners of the shelf. Suitable strips 23 of metal may be roveted to the horizontal flanges of opposite angles, or any other suitable webbing or sheet material may extend between the angles to provide the article-supporting surface of the shelf.

In accordance with this invention, the depending flanges of the angles 21 are provided with indents 24 which are received in the vertical slots of the brackets 4 with a wedge-like action. As shown particularly in Fig. 2, each indent is formed so that it provides an upwardly and outwardly inclined surface 25 and has a greater protuberance from the plane of the flange near the upper portion thereof than near the lower portion thereof. Accordingly, the indents may be received in the slots with a wedge-like action, thus preventing undesirable play between these parts as the shelf is fitted onto the bracket with the indents received in the slots in the manner indicated. The lower surfaces of the horizontal flanges of the angles may be supported upon the upper parts of the bosses 19, such an arrangement being shown in Fig. 2.

It is evident that the present invention affords a simple and inexpensive arrangement permitting

the firm engagement of a metal shelf with a supporting bracket in a knock-down construction of the type described.

I claim:

- 5 1. Bracket comprising a metal member having an opening through which a cylindrical upright may extend and having a vertical wall substantially tangential to said opening, the metal of the bracket affording a substantially vertical surface 10 extending inwardly at right angles to the inner surface of the wall, there being a horizontal web extending from said vertical surface to the wall, and an arcuate flange extending upwardly from said web but in spaced relation to the wall and 15 surface to cooperate therewith in defining similar vertical slots extending for a substantial fraction of the height of the bracket, said slots being gradually tapered so that they are wider at their upper parts than at their lower parts.

2. In a knock-down rack assembly, the combination comprising an upright, a metal bracket having an opening through which the upright extends and having a vertical wall extending substantially tangentially to said opening, the bracket providing a substantially vertical surface extending inwardly at right angles to the inner surface of the wall, and having a horizontal web extending between said surfaces and an arcuate flange extending upwardly from said web with its ends in spaced relation to said surfaces to cooperate therewith in defining similar vertical slots, and a metal shelf having depending metal flanges extending at right angles to each other and received in said slots, each of said flanges being provided with indents yieldably fitted into said slots with a wedge-like action. 5 10 15
